ELECTRO-HYDRAULIC BRAKE

Walter Sussebach, Olpe, Westphalia, Germany, assignor to Elektro-Mechanik-G.m.b.H., Westphalia, Germany

Filed Mar. 28, 1960, Ser. No. 18,176

Claims priority, application Germany Apr. 3, 1959

4 Claims. (Cl. 188—151)

The present invention relates to brakes and more in particular to electro-hydraulic brakes.

It is known in the art to provide brake for such machines as, for instance, cranes, hoists, conveyers and the like which are equipped with a brake-lifting device for lifting the brakes, whereupon the brakes are returned to their initial position by spring or weight means. The brake-lifting device is connected with the brake shoes by a lever arrangement and the lifting device is disposed laterally of the brake disk.

More recently electro-hydraulic devices have proved to be of particular advantage for use as brake-lifting apparatus. In particular, electro-hydraulic apparatus known under the name of "Eldro" and described, for example, in Patent 2,631,431, have a number of considerable advantages. They operate smoothly and quickly, are insensitive to great voltage drops and make it possible to use even small portions of the full stroke, thereby reducing the power consumption of the motor, particularly as soon as the piston comes to a standstill.

It is the object of the present invention to provide brake means making use of electro-hydraulic brake-lifting devices and combine them with a complete brake arrangement in such a manner that a complete and compact unit is obtained.

Further objects and advantages of the invention will become apparent as the description thereof proceeds.

The objects are achieved by the electro-hydraulic brake of the present invention according to which the brake frame is so constructed that it is simultaneously used as the pressure liquid container. The brake levers are moved by hydraulically operated members, such as particularly rotary wings, which are preferably positioned in the frame structure and within the liquid container. The motor pump unit of the apparatus can be either laterally attached to the liquid container or provided within the same. Furthermore, the rotary wings displacing the brake levers can be mounted either directly on the brake lever shaft or on a shaft connected with the brake lever shaft by transmission means.

As a pump it is possible to use hydrostatic pump means of the two-stage type of different capacities, that is, having a greater pump and a smaller pump, with the greater pump being switched off by contact means or at a predetermined pressure as soon as the rotary wings have reached their end positions.

The pressure liquid container is preferably positioned between the pair of brake levers, so as to obtain a compact unit. Both the pump unit and the motor can be provided with a ventilator for cooling the same.

The invention will be more fully appreciated upon the following description of the accompanying drawings, wherein—

FIGURE 1 is a side elevational view of the electro-hydraulic brake according to the invention;

FIGURE 2 is a plan view of the electro-hydraulic brake according to the invention;

FIGURE 3 is a fragmentary, side elevational view, partly in section, of the embodiment of FIGURE 1, illustrating the motor-pump unit as closely attached to the brake frame;

FIGURE 4 is a fragmentary, side elevational view, partly in section, of another embodiment of the electro-hydraulic brake of the invention, illustrating the motor-

2

pump unit as built into the structure of the brake frame;

FIGURE 5 is a fragmentary, side elevational view, illustrating transmission means for speeding up the rotary wing means relative to the brake lever shaft in the electro-hydraulic brake according to the invention;

FIGURE 6 is a fragmentary, side elevational view, illustrating contact means for switching off the greater pump in the electro-hydraulic brake of the invention.

The stationary brake frame 10 is constructed as a pressure liquid container and supports the two rotary wings 11, which latter are each connected with a shaft 17 supporting the brake levers 12 and 13, respectively. On the brake levers 12 and 13 are mounted the brake shoes 15. Each one of the levers 12 and 13 constitutes a unitary structure together with a rotary wing 11 and a shaft 17, the latter being rotatably mounted in frame 10 (see FIG. 2). An upper bar 16 connects the brake levers 12 and 13 at their upper ends, and bears a return spring 16a, for returning the brake levers and brake shoes into their initial positions after having been actuated by rotary wings 11. Resilient stop members 26 (whereof only one has been shown for the sake of simplicity) can be provided at the frame 10, in order to limit the movement of brake levers 12 and 13.

According to the invention the motor pump unit 14 also forms part of the frame structure or, as shown in FIGURE 1, is closely connected therewith. This unit 14 comprises the pump unit 18 with a pump 19 and pump 20, pump 19 having a greater capacity than pump 20. A pressure-operated valve 21 is connected with pumps 19 and 20. Unit 14 further comprises a motor 22, e.g. an electric motor, and an exterior ventilator 23 with cooling ribs so as to provide a better cooling of pump unit 18. A pipe conduit 24 connects the pumps with the rotary wings 11 so as to supply pressure liquid to the latter. Upon pumping of fluid, the rotary wings are driven thereby and the torque produced becomes effective in the brake levers 12 and 13 to release the brake. The frame 10 simultaneously constituting the pressure liquid container has leakage openings 25 for removing leakage liquid.

As will be seen from FIGURE 2, the pressure liquid container is constructed small enough to fit in between the pair of brake levers 12, 13.

Whereas in the embodiment of FIGURES 1 to 3 the motor-pump unit is adjacent the brake frame and connected therewith, for example, by its flange 27 to flange 28 of the brake frame 10, as shown in FIGURE 3, it is also possible, according to another embodiment, to have the motor unit built into the structure of the brake frame. This is illustrated in FIGURE 4, wherein pump unit 18 and motor 22 are mounted against cover plate 29 which latter is detachably mounted on the brake frame. The motor-pump unit is thus built into the frame structure of brake frame 10, and can be removed therefrom together with cover plate 29. Numeral 30 designates the level of pressure liquid in the brake frame 10, simultaneously constituting the pressure liquid container.

In operation, motor 22 drives pumps 19, 20, which convey pressure liquid through pipe conduit, so as to actuate rotary wings 11, which then operate the brake levers 12, 13, and thereby brake shoes 15. The movement of the brake levers is limited by stop members 26, and the brake levers are returned to their initial positions by return spring 16a. As soon as the end position of the rotary wings 11 has been reached, valve 21 causes the liquid conveyed by the greater pump to circulate without pressure, thereby greatly reducing the load on motor 22 and thus economizing on power consumption.

Whereas in FIGURES 1 and 2 the pump unit 18 is to be understood as comprising a two-stage pump system with geared pump means or vane-type pump means, it

is, of course, possible to use other, conventional hydrodynamic pumps, selected in a known manner according to the desired pressure values.

It will also be of advantage to provide transmission means between the brake lever shaft 17 and the rotary wings so as to speed up the movement of the latter; this will make it possible to operate at greatly reduced pressure.

Such transmission means may be of the general type, schematically illustrated in FIGURE 5; a gear 32 is connected with rotary wing 11 and meshes with gear segment 33 mounted on the brake lever shaft 17, supporting brake lever 13 with brake shoe 15. The gears are so dimensioned that the movement of rotary wing 11 is speeded up relative to brake lever shaft 17, thus making it possible to operate at far lower pressure.

A modification of the means for switching off the greater pump as soon as the rotary wing means have reached their end positions, is shown in FIGURE 6. Instead of pressure-dependent valve means 21 it is possible to provide contact means 34 as shown in FIGURE 6, for switching off pump 19, as soon as the rotary wing means 11 have reached end position.

The electro-hydraulically operated brake of the present invention offers considerable advantages over the art. Due to the fact that the brake frame is used as the pressure liquid container in the lifting unit, supporting two rotary wings operating the brake levers, and due to the fact that the motor pump unit is either closely attached to the frame or is provided within the same, a comparatively great cooling surface is obtained while, at the same time, the overall size of the entire brake structure is comparatively small. The brake shoes and the return spring means (16a) are easily accessible. Due to the small angular movement of the rotary wings which are in the order of less than $\frac{1}{2}$ °, the braking and lifting periods are extremely small. The fact that the rotary wings are mounted directly on the brake lever shaft and particularly the fact that transmission means can be provided speeding up the movement of the rotary wings makes it possible to operate at comparatively low pressures. It has been found that even for the greatest brakes needed, a pressure of not more than 8 atmospheres is sufficient. By making the liquid container so small as to fit inbetween the pair of brake levers a compact unit is obtained.

It will be understood that this invention is susceptible to modification in order to adapt it to different usages and conditions and, accordingly, it is desired to comprehend such modifications within this invention as may fall within the scope of the appended claims.

What I claim is:

1. Electro-hydraulic brake with a brake frame structure including a liquid storage container constituting a support base for the brake, a pair of brake levers having brake shoes operating above said container, shaft means for pivotally supporting said levers at said container, wall means in said container constituting a part thereof, hydraulically operated rotary wing means disposed and supported in said liquid container, and mechanical link-

age means including said shaft means for positively interconnecting said rotary wing means and said brake levers for torque conversion and transmission, hydrostatic pump means with a first and a second pump thereof, said first pump has a greater conveying capacity than said second pump, and means for switching off said first pump as soon as said rotary wing means engages said wall means.

2. Electro-hydraulic brake with a brake frame structure including a liquid storage container, constituting a support base for the brake, a pair of brake levers having brake shoes operated above said container, hydraulically operated rotary wing means disposed and supported in said liquid container, shafts supported in said container and supporting said brake levers, a first transmission gear mounted on one of said shafts, and a second transmission gear mounted on said rotary wing means meshing with said first gear, said first and second gear constituting a transmission means for decreasing the rotary speed of said lever relative to the rotary speed of said rotary wing means.

3. Electro-hydraulic brake with a brake frame structure including a liquid storage container constituting a support base for the brake, a pair of brake levers having brake shoes operating above said container, shaft means for pivotally supporting said levers at said container, wall means in said container constituting a part thereof, hydraulically operating rotary wing means disposed in said liquid container near said wall means, mechanical linkage means including said shaft means for positively interconnecting said rotary wing means and said brake levers for torque conversion and transmission, hydrostatic pump means with a first and a second pump thereof, said first pump has a greater conveying capacity than said second pump, and pressure-dependent valve means for switching off said first pump as soon as said rotary wing means engages said wall means in said container.

4. Electro-hydraulic brake with a brake frame structure including a liquid storage container, constituting a support base for the brake, a pair of brake levers pivotally supported at said container and having brake shoes operating above said container, hydraulically operated rotary wing means disposed in said liquid container, mechanical linkage means for positively interconnecting said rotary wing means and said brake levers for torque conversion and transmission, hydrostatic pump means with a first and a second pump thereof, said first pump has a greater conveying capacity than said second pump, and contact means for switching off said first pump when said rotary wing engages said contact switching means.
